UNITED STATES PATENT OFFICE.

GEORGE G. GREENBURG, OF CHICAGO, ILLINOIS, ASSIGNOR TO UNION TRUST COMPANY, OF JERSEY CITY, NEW JERSEY, A CORPORATION OF NEW JERSEY.

DESIGN FOR A PAPER-WEIGHT.

43,306.

Specification for Design.

Patented Dec. 3, 1912.

Application filed September 16, 1912. Serial No. 720,699. Term of patent 7 years.

To all whom it may concern:

Be it known that I, GEORGE G. GREENBURG, a citizen of the United States, residing at Chicago, in the county of Cook and State of Illinois, have invented a new, original, and ornamental Design for Paper-Weights, of which the following is a specification, reference being had to the accompanying drawing, forming part thereof.

Figure 1 is a front view of a paper weight embodying the new design. Fig. 2 is a rear elevation. Fig. 3 is a side elevation.

The improved design is characterized by a miniature reproduction of a round vault-

door *a* upon the front of which a building *b* is displayed and the back of which represents the back of such door including the radial bolts and usual parts thereon. This door is upon a short support *c* which rises from a base *d*.

I claim:

The ornamental design for a paper weight as shown and described.

GEORGE G. GREENBURG.
